LUMINAIRE

Edwin F. Guth, Jr., Ladue, Mo., assignor to The Edwin F. Guth Company, St. Louis, Mo., a corporation of Missouri

Filed Sept. 3, 1963, Ser. No. 76,437

Term of patent 14 years

(Cl. D48—31)

The undisclosed side is the same in appearance as the side shown in FIGURE 2.

The dominant features of my design reside in the portions shown in full lines.

I claim:

The ornamental design for a luminaire, as shown and described.
